[57] CLAIM

The ornamental design for a hanging file magazine holder apparatus, as shown and described.

DESCRIPTION

FIG. 1 is a side elevational view of a hanging magazine file holder apparatus showing my new design, the opposite side being a mirror image thereof;
FIG. 2 is a top plan view thereof;
FIG. 3 is a bottom plan view thereof; and,
FIG. 4 is a front elevational view, the rear view being a mirror image thereof.

FIG.2

FIG.1

FIG.3

FIG.4
